DESIGN FOR AN ELECTRIC HEATER

Clifford Knox and Alexander M. Dickie, Ontario,
Calif., assignors to General Electric Company,
a corporation of New York

Application July 7, 1938, Serial No. 78,325

Term of patent 14 years

To all whom it may concern:

Be it known that we, Clifford Knox and Alexander M. Dickie, citizens of the United States, residing at Ontario, in the county of San Bernardino, State of California, have invented a new, original, and ornamental Design for an Electric Heater, of which the following is a specification, reference being had to the accompanying drawing, forming a part thereof.

The accompanying drawing shows in Fig. 1

a front elevation of an electric heater embodying our new design, and in Figs. 2 and 3 a side elevation and a top plan view respectively of the electric heater of Fig. 1.

We claim:

The ornamental design for an electric heater, substantially as shown.

CLIFFORD KNOX.
ALEXANDER M. DICKIE.
